FLUE CAP FOR GAS STOVES

Filed Dec. 6, 1928

Joseph A. McCarthy. INVENTOR.

BY

D. Bryant
ATTORNEY.

UNITED STATES PATENT OFFICE

JOSEPH A. McCARTHY, OF JAMAICA, NEW YORK

FLUE CAP FOR GAS STOVES

Application filed December 6, 1928. Serial No. 324,272.

This invention relates to certain new and useful improvements in flue caps for gas stoves and relating to that class of devices for extracting and consuming soot and grease from the heating gases escaping from oven compartments or heating chambers and other areas around a gas stove, has for its primary object to mount a flue cap upon a laterally positioned flue outlet for a gas stove and to

10 direct heated gases through a grille or perforated area in the rear wall or back strip of a gas stove to discharge such gases into a room in a direction away from the adjacent room wall.

15 A further object of the invention is to provide a flue cap attachment for gas stoves assembled thereon in the manner above stated and to provide an arched hood or baffle of the stove backing strip overlying the grille

20 or perforated area for the outlet of gases to direct them forwardly of the stove and away from the adjacent room wall.

A still further object of the invention is to provide a flue cap attachment for gas stoves

25 in which the outlet end of the flue cap aligns with a perforated area formed in the back wall of the gas stove above the open burner top and below an upper shaft, the two outlets of the pipe extending over the heating chamber to a point rearwardly of the back wall of the stove burner top.

With the above and other objects in view that will become apparent as the nature of the invention is better understood, the same

30 consists in the novel form, combination and arrangement of parts hereinafter more fully described, shown in the accompanying drawing and claimed.

In the drawing:

40 Figure 1 is a fragmentary front elevational view of a gas stove having the flue outlet for the oven heating area disposed at the rear side of the stove with the flue cap mounted on the flue outlet elbow, and having its open upper end directed toward a hooded perforated area in the stove backing at the upper edge thereof;

45 Figure 2 is an enlarged detail view, partly in section, taken on line 2—2 of Figure 1, showing the mounted flue cap for directing

heat and gases from the flue outlet and forwardly through the perforated area in a backing strip;

50 Figure 3 is a fragmentary enlarged front elevational view showing the perforated portion of the backing strip, the open upper end of the flue cap facing the same and the lower cut away edge of the backing strip beneath the overlying hood; and

55 Figure 4 is a fragmentary front elevational view showing the burner top section of the gas stove with the flue pipe extension from the oven flue outlet having a cap flue thereon outletting through an area of perforations in the back wall of the burner section of the

60 stove.

65 The invention relates to a flue cap attachment for gas stoves of the type having an oven flue outlet in the rear wall thereof and said flue cap is adapted to be associated with the flue outlet in a manner for directing the heated gases in a direction forwardly of the stove, either through the stove backing strip above the oven or through the front wall of the stove above the burner top section for

70 directing the heated gases escaping from the stove through the flue outlet in a direction toward the center of the room and away from the room wall. In the form of the invention

75 illustrated in Figures 1 to 3, the flue cap is disposed between the flue outlet and the stove

80 backing strip, while in Figure 4, the flue cap is carried by an extension pipe leading from the flue outlet for discharging the heated

85 gases through a perforated area formed in the back wall of the stove above the burner top.

90 As illustrated, the gas stove 1 is provided with an oven section 2 threaded into the stove casing, comprising the rear wall 3 and top

95 wall 4 and spaced therefrom to provide an oven heating compartment 5, while the top of the stove 1 above the rear wall 3 is provided with the usual upstanding backing strip 6. The gas stove 1 further comprises a burner top section 7, a rear wall section 8 and an upper overhanging shelf 9, the backing strip 6 extending completely across the rear wall sections 3 and 8 as indicated in Figures 1 and 4.

The rear wall 3 of the oven section of the gas stove is provided with a flue outlet end in the form of an upwardly directed elbow spaced below the top wall 4 of the oven section of the stove, the horizontal open upper end of the elbow flue outlet 10 being provided with an inwardly directed shoulder or flange 11 for supporting a flue cap as shown in Figure 1. The flue cap comprises a tubular collar 12 having an enlarged curved head or hood 13 at its upper end with an open side directed toward the rear face of the backing strip 6 and lying juxtaposed to the strip and may be secured thereto in any suitable manner. If desired, steel wool or metal gauze may be inserted in the flue cap to extract soot and greases from heated gases flowing therethrough.

An arched hood 14 is carried by the front face of the backing strip 6 and is of substantially semi-circular formation in front elevation, the forward edge of the hood 14 inclining or tapering from its upper edge of greater width toward the lower edge of the backing strip 6 as shown more clearly by the reference numeral 15 in Figure 2. The backing strip 6 within the hood 14 is longitudinally cut away adjacent the stove top 4 between the opposite sides of the hood end to provide a bottom slot 17, while the remaining portion of the backing strip 6 within the hood 14 is perforated as at 18 over its entire area, this perforated part of the backing strip and the slot 17 spacing the open side of the flue cap hood 13. The heated gases escaping from the compartment 5 surrounding the oven 2 flow through the flue outlet elbow 10 and enter the flue cap for final discharge forwardly of the stove 1 through the slotted opening 17 and perforations 18, the heated gases being discharged in a direction toward the center of the room and away from the room wall. As above stated, any material, if desired, may be inserted in the flue cap for the extraction of soot and greases from the heated gases before discharge into the room.

In the form of the invention shown in Figure 4, the discharge outlet for the heated gases from the oven heating compartment 5 is through the back wall 8 rearwardly of the open burner top 7, the pipe section 19 extending from the flue outlet 10 and having an elbow 10^a upon its end to support the flue cap. The open side of the flue cap hood 13 faces the back wall section 8 and that portion of said wall aligned with the flue cap hood is provided with a plurality of perforations 18^a permitting the flow of discharge gases through the wall section 8. The overhanging shelf 9 of the stove constitutes a baffle or a hood performing the function of the hood 14 as shown in Figures 1 to 3 for further deflection of the escaping gases to direct them away from the adjacent room wall.

The above arrangement of flue caps is especially designed for association with gas stoves having the oven flue outlet in the rear wall thereof and directs the heated gases outletting from the oven heating area in a direction forwardly of the stove and away from the room wall, it having been found practical to prepare the backing strip 6 as above described to accommodate passage of the heated gases therethrough and also to construct the rear wall section 8 adjacent the open burner top 7 as described for the passage of heated gases. It will also be possible to dispose the open side of the hood 13 of the flue cap above the backing strip 6 for forwardly directing the heated gases.

While there are herein shown and described the preferred embodiments of the present invention, it is nevertheless to be understood that minor changes may be made therein without departing from the spirit and scope of the invention as claimed.

I claim:—

1. The combination with the outlet flue of a gas stove, of a flue cap adapted to be attached to the outlet flue and having a horizontal outlet outletting through a back part of the stove in a direction away from the back wall.

2. The combination with a gas stove having an outlet flue in the back part thereof, of a flue cap adapted to be attached to the outlet flue and having a horizontal outlet outletting through a back part of the stove in a direction forwardly of the stove.

3. The combination with a gas stove having an outlet flue in the rear wall and a top edge backing strip, of a flue cap adapted to be attached to the outlet flue and having a horizontal outlet outletting through the backing strip in a direction forwardly of the stove.

4. The combination with a gas stove having an outlet flue in the rear wall and a top edge backing strip, of a flue cap adapted to be attached to the outlet flue and having a horizontal outlet outletting through the backing strip in a direction forwardly of the stove, said backing strip having a plurality of perforations therein facing the flue cap outlet.

5. The combination with a gas stove having an outlet flue in the rear wall, a top edge backing strip, of a flue cap adapted to be attached to the outlet flue and having a horizontal outlet outletting through the backing strip in a direction forwardly of the stove, said backing strip having a plurality of perforations therein facing the flue cap outlet, and an arched hood carried by the backing strip overlying the perforated area.

6. The combination with a gas stove having an outlet flue in the rear wall, a top edge backing strip, of a flue cap associated with the outlet flue and outletting through

the backing strip in a direction forwardly of the stove, said backing strip having a plurality of perforations therein facing the flue cap outlet, and the lower edge of the backing strip being cut-away below the perforated area to provide a horizontal slotted opening extending across the flue cap outlet.

7. The combination with a gas stove having an outlet flue in the rear wall, a top edge backing strip, of a flue cap associated with the outlet flue and outletting through the backing strip in a direction forwardly of the stove, said backing strip having a plurality of perforations therein facing the flue cap outlet, an arched hood carried by the backing strip overlying the perforated area, and the lower edge of the backing strip being cut-away below the perforated area to provide a horizontal slotted opening extending across the flue cap outlet.

8. The combination with a gas stove having an outlet flue, a pipe section attached to the outlet flue, a back part of the stove having a plurality of perforations therein adjacent the upper end and a flue cap mounted on the pipe section, and outletting through the perforations in a direction forwardly of the stove and away from the room wall.

In testimony whereof I affix my signature.
JOSEPH A. McCARTHY.
